UNITED STATES PATENT OFFICE.

CARL T. WESTLIN, OF WESTFIELD, NEW JERSEY, ASSIGNOR TO OTIS ELEVATOR COMPANY, OF NEW YORK, N. Y., A CORPORATION OF NEW JERSEY.

ELEVATOR-CAR INCLOSURE.

Application filed June 21, 1927. Serial No. 200,367.

This invention relates to elevator car inclosures and particularly to elevator car inclosures for freight elevators.

One feature of the invention is to provide an inclosure of the above type that is of rigid construction and which requires a minimum of material.

Another feature of the invention lies in the provision of a car inclosure of the above type that is made up of standard parts produced on a quantity basis.

Still another feature of the invention is to provide a car inclosure that is readily constructed and installed and which is pleasing in appearance.

Other features and advantages will become apparent from the specification, taken in connection with the accompanying drawings wherein one embodiment of the invention is illustrated.

In the drawings:—

Figure 1 is a view in front elevation of an elevator car inclosure;

Figure 2 is a view with parts broken away taken along line 2—2 of Figure 1;

Figure 3 is a sectional view taken along line 3—3 of Figure 1; and

Figure 4 is an enlarged detail view of a portion of Figure 3.

Referring to the drawings, the inclosure is designated as a whole by the numeral 10. For convenience of description, the inclosure is illustrated as made up of three sides, namely, the left side 11, right side 12 and

rear side 13. According to the preferred arrangement, each side is made up of two vertically extending end panels 14 and one or more vertically extending intermediate panels 15, two intermediate panels being

shown. The outer vertical edges of both end panels 14 are joined, as by welding, to vertically extending angle bars 16. The inner vertical edge of each end panel 14 and both vertical edges of each intermediate

panel 15 are bent in such manner as to have a portion 17 in a plane at right angles to the panel and another portion 18 in a plane parallel to and overlapping the panel (see Figure 4), thus producing the same effect

as if these edges of the panels were reinforced with small vertically extending channels. This type of double bend is utilized in connecting adjoining panels.

In assembling one of the sides of the inclo-

sure, the panels making up this side are 55 grouped side by side with the portions 17 of adjacent panels in abutting relation. The panels are then joined by locking strips 20. These strips are of a cross section as shown in Figure 4 and are formed by folding over 60 the edges of an elongated flat sheet metal strip upon itself. These locking strips are slid lengthwise over the portions 18 of the adjacent panels, the strips being formed so as to grip the portions 18 when the parts 65 are in assembled relation. These strips extend the full length of the panels as shown in Figure 2. With the locking strips in place, the panels are joined at the bottom by an angle bar 22 and at the top by an angle bar 23, these angle bars being secured to the panels as by welding. The horizontal leg 24 of the bottom angle bar 22 extends inwardly of the car while the horizontal leg 25 of the upper angle bar 23 extends outwardly of the car. With the panels thus connected, a strong and rigid side of the inclosure is obtained. The corner angle bars 16 of the side of the inclosure are secured to the end panels in such manner as to provide 80 right and left angles.

With all three sides made up, they are grouped together, as shown in Figure 3, and joined as by bolts 19 extending through the abutting legs of adjoining right and left angle bars 16. The inclosure is secured to the car platform 26 as by screws 27 extending through the horizontal legs 24 of the bottom angle bars 22. A hole or pocket may be provided in one of the panels to receive a flush type car switch, such a hole, designated 28, being illustrated as formed in the forward end panel 14 of the right side 12 of the inclosure (see Figure 2).

It is preferred to make the intermediate 95 panels of two different widths. Also, it is preferred to make certain of the end panels wide enough so that they may be cut to any required width with the remaining end panels of a standard width. With these 100 panels, an inclosure having its sides of any desired widths may be made. It is also preferred to make all the panels of the same height. Thus, standard panels may be kept in stock and inclosures of any desired size 105 may be assembled from them on short notice. Furthermore, with all panels the same height and with their widths standardized,

the number of different panels to be kept in stock is minimized and these parts may be produced on a quantity basis.

It is preferred that the height of the panels 5 be six feet or slightly above, thus satisfying the requirements of practically all statutes. The vertical corner angle bars 16, however, are extended in height beyond the panels except under certain conditions which will be 10 explained later. The top portion 30 of both corner angle bars 16 for the right and left sides of the inclosure is bent over as shown in Figure 2. These vertical angle bars are joined by horizontal angle bars 31 connected 15 thereto, as by bolts extending through the bent over portions 30.

The inclosure may or may not be provided with a top, depending upon the requirements of the particular installation. Where no top 20 is provided, the inclosure may be braced above the panels as by tie rods extending from the horizontal angle bars 31 to the crosshead of the car framework (not shown). The tops, when specified, may be made up of 25 a plurality of perforated sheet steel panels 32 secured, as by welding, to cross angle bars 33. These cross bars are in turn secured to the horizontal angle bars 31, as by bolts 34 and clips 35. The front top panel may be 30 set back from the opening a certain distance, as shown in Figure 2, where building regulations require it. Where sheaves are mounted on the crosshead of the car framework, it is preferred to provide a solid top center 35 panel with bent up sides to form a pan to protect the car from oil and grease that may drop from the crosshead sheaves and boxes.

If it is desired to have the car inclosed to a greater height than that provided by the 40 solid panels 12 and 14, additional side panels 36 may be provided. These panels may be of perforated sheet steel secured, as by welding, to horizontal angle bars 37. At their ends, these panels may be secured, as 45 by bolts, to the corner angle bars 16. The lower angle bars 37 may be joined to the top angle bars 23 of the solid panel sides, as by bolts. Also, the top angle bars 37 of the right and left side additional panels may be 50 secured, as by bolts, to the angle bars 31. Where a top is provided, the top angle bar 37 of the rear side additional panel may be secured, as by bolts, to the back cross angle bar 33.

55 In case of a small inclosure with no additional side panels or top, it is found that the inclosure may be braced sufficiently by connecting the top angle bars 23 of the right and left sides to the sides of the car framework 60 work without extending the corner angle bars 16 the additional height. It is preferred to provide this connection for all arrangements of the inclosure and also to connect angle bars 31 to the sides of the car framework 65 where the corner angle bars are extended.

It will be seen that, with the above arrangement, the rear side 13 may be easily removed at any time without requiring any changes to be made in the sides 11 and 12. Furthermore, the inclosure may be made up in the 70 first instance of only two sides, or even only one side, if such be the requirements of the particular installation. The inclosure may be packed for shipping with the panels separated or with the sides assembled, as occasion 75 demands. Where the separate panels are shipped, the sides may be assembled on the job by means of bolts instead of welding. It will be seen that the panels are of very simple construction and therefore can be 80 easily made at a minimum cost. Furthermore, the sides may be assembled in a minimum of time by use of the locking strips 20 owing to the fact that this method of assembling eliminates a large percentage of the 85 welding formerly required. It is to be noted that the channel-like arrangement of the vertical edges of the adjoining panels makes a very strong construction and together with the steel locking strips makes up a rigid steel 90 inclosure with a minimum amount of material.

As many changes could be made in the above construction and many apparently 95 widely different embodiments of this invention could be made without departing from the scope thereof, it is intended that all matter contained in the above description or shown in the accompanying drawings shall 100 be interpreted as illustrative and not in a limiting sense.

What is claimed is:

1. An elevator car inclosure comprising; a pair of adjoining panels, each panel having its edge adjacent the other panel bent to 105 form a portion in a plane at right angles to the panel and further bent to form a second portion overlapping the panel and in a plane parallel to the plane of the panel; and a locking strip extending across the second portions and bent around their edges for securing said panels together with their first portions in abutting relation.

2. An elevator car inclosure comprising; a pair of adjoining vertical sheet metal panels 115 arranged in a vertical plane, each panel having its vertical edge adjacent the other panel bent outwardly into a plane at right angles to the panel to form a flange, each flange being bent at its outer edge into a plane 120 parallel to its panel and overlapping the same; an elongated vertical sheet metal locking strip having its vertical edges folded over upon itself and arranged to be slid lengthwise over the outer edges of the flanges 125 and to grip the same to secure the panels together with their flanges in abutting relation; and horizontal members, each secured to both panels.

3. An elevator car inclosure comprising; a 130

pair of adjoining vertical sheet metal panels arranged in a vertical plane, each panel having its vertical edge adjacent the other panel bent outwardly into a plane at right angles to the panel to form a flange, each flange being bent at its outer edge into a plane parallel to its panel and overlapping the same; an elongated vertical sheet metal locking strip having its vertical edges folded over upon itself and arranged to be slid lengthwise over the outer edges of the flanges and to grip the same to secure the panels together with their flanges in abutting relation; and a pair of horizontally extending angle bars, one secured to both panels at the bottom and the other secured to both panels at the top.

4. A side of an elevator car inclosure comprising; a plurality of adjoining vertical sheet metal panels arranged in a vertical plane, each of said panels having its vertical edge adjacent another of said panels bent outwardly into a plane at right angles to the panel to form a flange, each flange being bent at its outer edge into a plane parallel to its panel and overlapping the same; elongated vertical sheet metal locking strips of a number one less than the number of panels, each strip having its vertical edges folded over upon itself and arranged to be slid lengthwise over the outer edges of the flanges of a pair of adjoining panels, for securing said panels together with the flanges of adjoining panels in abutting relation; a pair of horizontally extending angle bars, one secured to all of said panels at the top and the other secured to all of said panels at the bottom; and a pair of vertically extending angle bars, one secured to the outer vertical edge of an end one of said panels with its outer leg extending outwardly and the other secured to the outer vertical edge of the other end one of said

panels with its outer leg extending outwardly, providing right and left angles at the outer edges of the inclosure side.

5. An elevator car inclosure having a plurality of sides arranged at right angles, each side comprising, a plurality of adjoining vertical sheet metal panels arranged in a vertical plane, each of said panels having its vertical edge adjacent another of said panels bent outwardly into a plane at right angles to the panel to form a flange, each flange being bent at its outer edge into a plane parallel to its panel and overlapping the same, elongated vertical sheet metal locking strips of a number one less than the number of panels, each strip having its vertical edges folded over upon itself and arranged to be slid lengthwise over the outer edges of the flanges of a pair of adjoining panels, for securing said panels together with the flanges of adjoining panels in abutting relation, a pair of horizontally extending angle bars, one secured to all of said panels at the top and the other secured to all of said panels at the bottom, and a pair of vertically extending angle bars, one secured to the outer vertical edge of an end one of said panels with its outer leg extending outwardly and the other secured to the outer vertical edge of the other end one of said panels with its outer leg extending outwardly, providing right and left angles at the outer edges of the inclosure side; and means for securing adjacent sides together at the corners with the outwardly extending leg of a vertical angle bar of one of said sides abutting the inner leg of a vertical angle bar of the adjacent side.

In testimony whereof, I have signed my name to this specification.

CARL T. WESTLIN.
